UNITED STATES PATENT OFFICE.

WALTER ARNDT LUCAS, OF HAWTHORNE, NEW JERSEY, ASSIGNOR, BY MESNE ASSIGNMENTS, TO THE T. H. SYMINGTON COMPANY, OF NEW YORK, N. Y., A CORPORATION OF DELAWARE.

TRUCK SIDE FRAME.

Application filed April 29, 1920, Serial No. 377,441. Renewed May 25, 1923.

To all whom it may concern:

Be it known that I, WALTER A. LUCAS, a citizen of the United States, residing at Hawthorne, in the county of Passaic and State of New Jersey, have invented certain new and useful Improvements in Truck Side Frames; and I do hereby declare the following to be a full, clear, and exact description of the invention, such as will enable others skilled in the art to which it appertains to make and use the same.

The invention relates to trucks for railway vehicles and more particularly to new and useful improvements in the construction of side frames for arch bar trucks.

The principal object of my invention, broadly considered, is to strengthen and simplify the construction of arch bar side frames. To this end the primary feature of the invention consists in a combined arch bar and journal box tie member of simple and novel form.

Other features of the invention will hereinafter appear from the detailed description of the single embodiment of my invention, which is shown in the accompanying drawings, wherein,

Figure 1 is an elevational view of a symmetrical portion of a truck side frame embodying my invention.

Figure 2 is a top view of the combined tension or lower arch members showing the same in assembled position, the upper arch member and the strut column being omitted.

Figure 3 is a sectional view.

Figure 4 is an end view of the upper portion of the side frame showing the relation of the arch members to the journal box seat.

Throughout the specification and drawings like parts are designated by like reference characters.

The truck side frame 1 is provided with a top arch member which is conveniently formed as a rectangular bar 2, and a lower arch member which preferably comprises a pair of flanged bars 3, 3. Interposed between the arch members intermediate the ends thereof is a strut member 4 which has for convenience been illustrated as comprising a pair of columns 5 connected by the conventional form of spring plank 6, only one of the columns being illustrated in the drawings, it being understood that the truck side frame is symmetrical on the center line.

The ends of the arch members 2 and 3 are connected to a journal box seat 7, the said seat forming a support for the upper wall of the journal box 8. The journal box seat illustrated in the drawings preferably comprises a hollow box like casting having aligned holes in the top and bottom webs 9 to receive the journal box bolts 10, the said bolts passing through and firmly connecting the upper arch bar to the said seat. The lower arch members are preferably riveted to the side webs 11 of the said seat, as clearly shown in Fig. 4.

The lower arch or compression members 3 are preferably formed as Z-bars having their upper flanges 12 extending towards each other and their lower flanges 13 extending laterally of the truck frame in opposite directions. To conveniently form the journal box tie bars I preferably cut through the web 14 of each Z-bar from the ends of the said bars to a point near the adjacent strut column. After the Z-bar is cut the lower flange 13 is bent away from the remaining portion of each bar 3 so that the end portions of each Z-bar are spaced apart a distance approximately equal to the height of the journal box 8 plus the height of the journal box seat 7. The cut through the web of each Z-bar is preferably made in line with the upper face of each flange 13 for the major portion of the cut and at least adjacent the outer end portions thereof. By this means I form at each end of the said arch bar 3 a substantially flat plate 15. These plates are then bent inwardly as shown at 16 so that the adjacent ends of the plates 15 formed from the Z-bars will overlap and underlie the journal box 8 to which they are connected by means of the journal box bolts 10. The said bolts are adapted to pass through aligned openings in both of the adjacent plates 15, said plates being held to the journal box by the nuts 17 provided on the ends of the bolts 10. By making the tie members integral with the lower arch members the number of parts in the truck side frame is materially reduced and all possibility of a loose connection between these members is avoided, thus greatly strengthening the side frame.

While I have illustrated and described the combined tension and journal box tie bars as being formed from Z-shaped members, I

do not intend to be limited to this form of member, and wish it to be understood that other forms of rolled shapes may be advantageously employed in this connection.

5 Having now fully described my invention, what I claim and desire to secure by Letters Patent is:—

1. A truck side frame comprising a top and a plurality of spaced flanged bottom 10 arch members, and means for uniting said members adjacent the journal boxes, each of said bottom arch members being made from an integral bar split in a suitable manner to form journal box tie members therefrom.

2. A truck side frame comprising a top and a plurality of bottom arch members, means for uniting said members adjacent the ends thereof, and journal box tie members integral with each of the bottom arch members, the end portions of adjacent tie members being adapted to overlap.

3. A truck side frame comprising a top and a plurality of flanged bottom arch members, one flange of each of the said bottom members being spaced from the end portions thereof and being adapted to form a journal box tie member.

4. A truck side frame comprising a top 30 arch bar and a plurality of lower arch members, the latter each being formed from a Z-bar.

5. A truck side frame comprising a top arch bar and a plurality of lower arch members, the latter each being formed from a Z-bar the upright webs thereof being spaced apart and the upper flanges thereof extending toward each other.

6. A truck side frame comprising a top

arch bar and a pair of Z-bars forming the 40 lower arch members, one of the flanges of each of the said Z-bars adjacent the ends thereof being spaced therefrom and adapted to extend under the adjacent journal box.

7. A combined arch and journal box tie 45 bar for trucks comprising a flanged member having a united central portion and divided end portions, the said divided end portions being adapted to be spaced apart to receive a journal box between the same, the cross 50 sectional area of the said end portions being the same as the cross sectional area of the united central portion.

8. In a truck side frame, the combination 55 with a compression member, a journal box connected thereto and a strut, of a plurality of tension members engaging said strut and connected to said journal box, each tension member comprising a beam having a plurality of flanges extending laterally from the web, the said web being cut for a portion of its length whereby one of said flanges may extend above and the other below the said journal box, and means 60 for connecting each of said flanges to the 65 said journal box.

9. A combined tension and tie bar for 70 truck side frames, comprising a beam provided with a plurality of flanges extending from the upper and lower edges of the web thereof, said flanges diverging from a point adjacent the center of length of the said beam and adapted to extend above and below the journal box.

In testimony whereof I affix my signature.

WALTER ARNDT LUCAS.
